LIGHTING CASING

Edwin F. Osborne, Jr. Houston, Tex., assignor to Esquire, Inc., New York, N.Y., a corporation of Delaware

Original design application Nov. 8, 1967, Ser. No. 9,331.
Divided and this application Feb. 28, 1968, Ser. No. 11,225

Term of patent 14 years

U.S. Cl. D48—20.6
Int. Cl. D26—03

FIGURE 1 is a front perspective view of a lighting casing constructed in accordance with one embodiment of my design.

FIGURE 2 is a front perspective view of a lighting casing constructed in accordance with another embodiment of my design.

The undisclosed sides of the casings shown are plain except for the ridge-and-recess design.

The support pole in broken lines in FIGURES 1 and 2 is shown for illustrative purposes only.

This application is a division of my copending application Ser. No. D9,331, filed Nov. 8, 1967.

I claim:

The ornamental design for a lighting casing, as shown and described.
